ATTORNEYS

UNITED STATES PATENT OFFICE.

GEORGE WARREN CAMP, OF MOUNT VERNON, NEW YORK, ASSIGNOR TO WARD
LEONARD ELECTRIC COMPANY, A CORPORATION OF NEW YORK.

RESISTANCE UNIT.

1,320,200.

Specification of Letters Patent. Patented Oct. 28, 1919.

Application filed February 20, 1917. Serial No. 149,720.

To all whom it may concern:

Be it known that I, GEORGE W. CAMP, a citizen of the United States, residing at Mount Vernon, in the county of Westchester and State of New York, have invented certain new and useful Improvements in Resistance Units, of which the following is a specification.

The principal object of my invention is to provide a new and improved resistance unit of rugged and convenient design. Another object of my invention is to provide a resistance unit adapted to have one end secured in a convenient manner to a support with both terminals disposed at the other end. These objects and others will be made apparent in the following specification and claims taken in connection with the accompanying drawings. In these drawings I have illustrated one specific embodiment of my invention, but it will be understood that the invention is defined in the appended claims.

Referring to the drawings, Figure 1 is a perspective view of one of my improved resistance units mounted on a support.

Fig. 2 is a section of the same.

Fig. 3 is a top view of one unit.

Figs. 4, 5 and 6 are views of detail parts at certain stages in the manufacture and assembly of the unit.

On the earthenware tube 11, a definite length of resistance wire 12 is wound in a single layer with the turns spaced apart. The initial end of this length of resistance wire 12 is fastened by a clip 15 to the stranded band 14 and the band 14 is laid in the trough or groove 13 of the terminal member 16, then wrapped around one end 40 of the tube 11, and its ends tightly twisted together as at 17 in Fig. 3. The terminal member 13—16 is made from a sheet metal stamping as shown in Fig. 5, and this is finally shaped as shown in Fig. 6. Thus a 45 projecting terminal lug 16 is provided conductively connected to the initial end of the resistance conductor 12, and firmly mounted on one end of the tube 11. After the resistance conductor 12 is wound on the tube 11, 50 the final end is attached by a clip 15' to a

stranded band 14', and a terminal member 16' has its groove 13' engaged under the band 14', after which its ends are twisted together, similarly to 17 for band 14. The terminal member 16' can be adjusted around 55 the tube 11 before the band 14' is fastened, so as to bring it in proper angular relation to the lug 16. By referring to Fig. 2, it will be seen that the lug 16' is passed through the tube 11 before the band 14' is fastened in 60 place.

The inner earthenware tube 18 has its outer face flattened on one side to fit against, the terminal member 16'. This inner tube 18 fits snugly inside of the tube 11, and 65 against member 16'.

After the parts are assembled as just described, a coating of enamel 19, or other insulating adhesive material, is applied over all the parts except the interior of the tube 70 18 and the two projecting lugs 16 and 16'. Thus the parts are all rigidly secured together and a simple conveniently shaped rugged resistance unit is provided with both its terminals exposed at one end extending 75 radially at a convenient angle. This unit and others like it may be supported on a bar 20 by means of long screws 22 engaging the screw threaded holes 21 in the bar 20. Under the head 24 of each screw 22 is a suitable 80 cushion washer 23. The lugs 16 and 16' as shown in Fig. 1 may have conductors attached to them, so as to put the resistance wire 12 in series therewith. It will be noticed that even if the bar 20 is of conductive material, there need be no conductive connection to it from the circuit of the resistance wire 12, for the screw 22 contacts only with the inner tube 18 which is of insulating material. By bringing terminal 85 member 16' from one end through the inside of tube 18 to the other end, both terminals are brought out at one end so that they can be conveniently engaged by the conductors leading to the resistance unit. 90 The inner tube 18 holds the parts firmly in a definite relation for enameling and insures that no ordinary stresses to which the lugs 16 and 16' may be subjected can loosen them or crack the enamel. For certain 95 100

classes of work it may be desirable to have the two lugs 16 and 16' stand at a definite angle and in the drawing this angle is shown as about 75 degrees. The earthenware tubes 11 will vary slightly in size and a definite length of wire wound many times thereon would have its two ends come at different angular relations. However this may be, the terminal 16' can be adjusted in position during the assembly of the parts so as to bring the two terminals 16 and 16' at the proper angular relation, without unduly altering the effective length of conductor 12 between the two clips 15 and 15'.

15 I claim:—

1. In combination, a tube of insulating material, a resistance conductor wound thereon, a terminal member from one end of the resistance conductor through the inside 20 of the tube, and an inner tube of insulating material, said terminal member lying outside the inner tube.

2. In combination, a tube of insulating material, a resistance conductor wound 25 thereon, two conductive bands one around each end of the tube with the respective ends of the resistance conductor attached thereto, and two terminal members connected to the respective bands, one such member being 30 longer than the other and extending through the inside of the tube and projecting from the other end thereof.

3. In combination, a tube of insulating material, a resistance conductor wound 35 thereon, two conductive bands one around each end of the tube with the respective ends of the resistance conductor attached thereto, and two terminal members connected to the respective bands, one such member being 40 longer than the other and extending through the inside of the tube, the ends of both said members projecting radially from the same end of the tube and at a definite angle with one another.

45 4. In combination, a tube of insulating material, a resistance conductor wound thereon, a terminal member from one end of the resistance conductor through the inside of the tube, an inner tube of insulating material, said terminal member lying outside the inner tube, a support for the foregoing assembled elements and a screw through the inner tube engaging said support.

5. In combination, a tube of insulating 55 material, a resistance conductor wound thereon, a terminal member from one end of the resistance conductor through the inside of the tube, a support for the foregoing assembled elements, a screw through said tube 60 engaging said support and means within said tube insulating the screw from the said terminal member.

6. In combination, a tube of insulating

material, a resistance conductor wound thereon, a terminal member from one end of 65 the resistance conductor through the inside of the tube, means within said tube bracing said terminal member and a coating of enamel over the tube and the resistance conductor wound thereon. 70

7. In combination, a tube of insulating material, a resistance conductor wound thereon, a terminal member from one end of the resistance conductor through the inside 75 of the tube, means within said tube bracing said terminal member and a coating over the tube and the resistance conductor wound thereon.

8. In combination, a tube of insulating material, a resistance conductor wound 80 thereon, two conductive bands, one around each end of the tube with the respective ends of the resistance conductor attached thereto, two terminal lugs connected to the respective bands, a support for the foregoing assembled 85 elements and a screw through said tube engaging said support, said lugs standing in definite angular relation to said support irrespective of the angular relation of the points of attachment of the ends of the resistance conductor with said bands. 90

9. In combination, a drum of insulating material, a resistance wire of definite length wound thereon, two bands around respective 95 ends of the drum, clips fastening the ends of the resistance wire to said bands, and two radial terminal lugs bound under the bands at a desired definite angular relation to each other irrespective of the angular relation of the ends of the resistance wire. 100

10. In combination, a drum of insulating material, a resistance wire wound thereon, a stranded band around one end of the drum, a clip pinching one end of the resistance wire securely to said band, a terminal member having a groove engaged by said band and a lug projecting radially therefrom at any desired angular position, the ends of said band being twisted tightly together and thereby securing the said terminal member firmly on the drum. 105

11. The method of assembling and securing a resistance wire on a drum to form a resistance unit, which consists in fastening the initial end of said wire to a band at one 110 end of the drum, binding a terminal lug under said band, winding the wire on the drum, securing its final end to another band at the other end of the drum, placing another terminal lug under the last mentioned band at a definite angular relation to the first lug, and fastening the said last mentioned band in place.

12. In combination an insulating tube having a resistive conductor wound thereon, a hollow insulator placed therein, a conduc-

5 tor attached at one end of said resistive conductor and running the length of the tube and between the tube and the insulator, and an adhesive insulating coating which fastens the tube and the insulator together.

13. In combination, a tube of insulating material, a resistance conductor wound thereon, a terminal member extending radi-

ally from one end of the resistance conductor at one end of said tube, and another terminal member from the other end of said resistance conductor at the other end of said tube extending through the inside of the tube and bent and continued radially therefrom.

GEORGE WARREN CAMP.
